UNITED STATES PATENT OFFICE.

FREDERIC W. PENDERGAST, OF WALTHAM, MASSACHUSETTS.

FILTER.

SPECIFICATION forming part of Letters Patent No. 788,145, dated April 25, 1905.

Application filed April 9, 1904., Serial No. 202,290.

To all whom it may concern:

Be it known that I, FREDERIC W. PENDERGAST, a citizen of the United States, residing at Waltham, in the county of Middlesex and State of Massachusetts, have invented certain new and useful Improvements in Filters, of which the following is a specification.

My invention relates to improvements in filters, and has for its object the provision of a filter which may be readily and quickly cleaned without detaching the same from the water-supply pipe, which will thoroughly cleanse the water filtering therethrough, and by reversing the current of the water passing through the water-filter the substances that may collect on the filtering-disk are washed away. This object is attained by a simple half-turn of the filter on its pivoted point, which in the example illustrated is the valve, and all back pressure on the faucet to which the filter is connected is avoided.

In using the filter where it is desired to apply the same to the faucets now in use the faucet is first unscrewed from the water-pipe, the faucet removed, and the filter is connected at one side to the supply-pipe, and then the faucet is screwed to the other side of the filter, thus interposing the filter between the supply-pipe and the faucet, as shown by dotted lines in Figure 1.

My invention consists in certain novel features of construction and combinations and arrangement of parts, as hereinafter described, and pointed out in the claims.

In the drawings, Fig. 1 is a perspective view of my device as applied to a faucet and supply-pipe, the faucet and supply-pipe being shown in dotted lines. Fig. 2 is a view, partly in section, with the cover removed. Fig. 3 is a sectional view on line 3 3, Fig. 2. Fig. 4 is a sectional view on line 4 4, Fig. 2.

The filter consists of a casing 1, provided with a handle 2, the detachable screw-threaded side piece 3 having lugs 3' thereon for convenience in attaching or detaching said side piece, and the filtering-disk 4, located in said casing and held therein between the packing-rings 5 and 6, and lugs 7 and 8 on the sides of the casing. The casting is extended at its top, as at 9, and provided with a valve-seat

10, into which is fitted the tapered valve-plug 11, having outer screw-threads 12 at its inner end and inner screw-threads 13 at its outer end for attachment to the supply-pipe and faucet, respectively, as illustrated in Fig. 1. 55 A partition 11' is located in the valve-plug and divides said valve into two chambers. On the threads 13 are located two nuts 14 and 15 for tightening the filter-casing on the valve-plug. Washers may also be interposed between the filter and pipes to make a close joint. The valve-plug is further provided with two ports 16 and 17 at each side of the partition 11', located on opposite sides of the plug, as shown in Fig. 4. The valve-seat 10 is likewise provided with two ports 18 and 19, located diametrically opposite each other and in the same plane, said ports leading, respectively, to passages 20 and 21 in the extended portion of the casing, and these ports 18 and 19 are as long as the distance between the top of the port 16 to the bottom of the port 17 in the valve-plug, so that whichever way the filter may be turned on the valve-plug a pair of the different ports will register. As will 75 be seen in Figs. 2 and 3, passage 21 opens to the near side of the disk and passage 20 opens to the far side of said disk. The valve-seat portion 9 is provided with two shoulders 22, located diametrically opposite each other, 80 which contact with a stop-pin 23, located on one end of the valve-plug, thus limiting the movement of the filter when turned by the handle and causing the filter to stop at just the right point in its revolution whichever 85 way it may be turned.

The operation of the filter is as follows: With the handle pointing downward, as in position Figs. 1 and 2, the water flows through the left-hand port 18, through the chamber or 90 passage 20 into the back part 24 of the filter-casing, and thence through the disk into the chamber 25 of the casing on the other side of the disk, up through the passage 21, through the right-hand port 17, and out through the 95 faucet, all foreign substances having been left behind as the water passed through the filtering-disk. To reverse the water-flow and clean off the substances which may have been filtered onto the disk, turn the filter half-way around 100

on the valve-plug as a pivot, so that the handle is at the top, the movement being limited by the lugs 22 and pin 23. This movement forces the water to pass through the valve-
5 port 17, valve-seat port 19, and passage 21 to the chamber 25, through the filtering-disk, chamber 24, passage 20, and port 18, thence through the valve-plug and faucet.

Having thus fully described my invention,
10 what I claim, and desire to secure by Letters Patent, is—

1. The combination with a casing, of a filter therein forming chambers, a screw-plate having a central lug thereon, a complementary lug on the casing at the opposite side of the filter for securing said filter, an extension at the top of the casing having a valve-seat with elongated ports, a stationary valve-plug with a transverse partition therein and ports ar-
15 ranged at each side of said partition out of alinement and adapted to register with said elongated ports, separate communication being established between said chambers and elongated ports, a pin on the valve-plug and a shoulder on the casing to limit the move-
20 ment of the casing, and means whereby the
25

flow of water through the filter may be re-versed.

2. The combination with a casing and a filter forming chambers therein, a removable plate 30 having a lug thereon and a complementary lug on the casing for securing the filter, an extension formed on said casing having a tapered valve-seat with elongated ports on opposite sides thereof, a stationary valve-plug, 35 a transverse partition in the plug and ports at each side thereof to register with the elongated ports, passages connecting the chambers separately with the elongated ports, a handle integral with the casing, said casing 40 being pivotally supported on the valve-plug and adapted to be rotated bodily to reverse the flow of water through the filter, a pin in the valve-plug, and a shoulder on the casing to limit the movement of the casing. 45

In testimony whereof I affix my signature in presence of two witnesses.

FREDERIC W. PENDERGAST.
